Primary Examiner — Sandra Snapp*Assistant Examiner* — Mehri F Bajoul(74) *Attorney, Agent, or Firm* — Cambridge Technology Law; Maura K. Moran(57) **CLAIM**

The ornamental design for a paw-shaped brush, as shown and described.

DESCRIPTION

FIG. 1 is a front perspective view of a paw-shaped brush, showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown in the drawings depict portions of the paw-shaped brush that form no part of the claimed design.
